GOVERNOR FOR FIRE-PUMP APPARATUS

Ben D. Barton, Battle Creek, Mich., assignor to
 American Steam Pump Company, Battle Creek,
 Mich., a corporation of Michigan

Application August 26, 1935, Serial No. 38,008

3 Claims. (Cl. 137—153)

This invention is a novel governor, which I term an engine horse-power and centrifugal-pump maximum pressure governor having two primary functions: (1) to automatically limit the horse-power output of the engine without necessarily restricting the speed of rotation of the crank shaft, and (2) to automatically limit the pressures created by a pump to a predetermined level, said governor being adapted to be installed in the fuel intake manifold of a prime mover, preferably disposed between the intake manifold and carburetor of an internal combustion engine used in connection with fire-pump apparatus, said governor being particularly although not necessarily adapted for use in connection with fire-pump apparatus such as the portable type shown in my U. S. Letters Patent No. 1,538,881 dated May 26, 1925, and Reissue Patent No. 17,538 dated December 24, 1929; which apparatus consists briefly of a centrifugal fire-pump mounted upon the front end of an automobile chassis and directly driven through suitable clutch mechanism by the main crank shaft of the engine of the vehicle.

I will explain the invention with reference to the accompanying drawings which illustrate several practical embodiments thereof to enable others familiar with the art to adopt and use the same; and will summarize in the claims the novel features of construction, and novel combinations of parts, for which protection is desired.

In said drawings:—

Fig. 1 is an elevation showing the assembly of my novel governor in a fire pump apparatus such as shown in my aforesaid patents, the governor being installed between the intake manifold and carburetor of the engine, and also showing the pipe connection from the governor to the pressure side of the pump.

Fig. 2 is an enlarged bottom plan view of the governor, detached.

Fig. 3 is a vertical section through the valve operating mechanism of the governor, along the line 3—3, Fig. 2, and showing the parts in normal position in which the valve is in fully open position.

Fig. 4 is a view similar to Fig. 3 but showing the parts in the positions assumed when the governor is acting to restrict the horse-power of the engine.

Fig. 5 is a view similar to Figs. 3 and 4 but showing the parts in the positions assumed under a predetermined pressure equal to the higher pressure required of the individual unit.

Fig. 6 is a plan view of a governor valve body

modified for use on a V-type engine having a double intake manifold instead of a single manifold.

Fig. 7 is a detail perspective view.

Fig. 1 shows the invention applied to a fire-apparatus assembly comprising an internal combustion engine A having an intake manifold B and carburetor C, the engine being mounted on the chassis D of the vehicle. A centrifugal pump E is also mounted on the chassis in advance of the engine A, the impeller of pump E being driven directly through a clutch or transmission shaft F by the main crank shaft of the engine.

The governor shown in Figs. 1—5 comprises a valve body 1 having upper and lower coupling flanges 1a, 1b, perforated as at 1c to receive bolts or the like for connecting the valve body to the mating coupling flanges of the intake manifold B and carburetor C of the engine whereby in installing the governor it is merely necessary to disconnect the carburetor from the intake manifold, then insert the governor valve body 1 in place, and bolt the mating flanges of the parts together.

Disposed vertically of the valve body is a bore 2, and extending transversely through the bore is a shaft 4 carrying a butterfly valve 5 within the bore adapted when shaft 4 is rotated to open or close the bore to control the quantity of fuel passing from the carburetor into the intake manifold.

Shaft 4 extends through one side of the body and is provided on its outer end with a disk 7 having a pin 8 eccentrically mounted thereon, said pin being adapted to be engaged by a transverse slot in the head of a plunger 9 mounted in a cylinder 10, the housing of which is connected to or integral with the side of the valve body 1. Plunger 9 (Fig. 7) has an enlarged head 9a (Fig. 7) adjacent its outer end provided with a transverse slot 9b in one side receiving pin 8, which pin is so disposed in disk 7 that when head 9a of plunger 9 is in its normal position, abutting against the adjacent end of cylinder 10, the butterfly valve 5 will be disposed in its fully open position and any movement of the plunger (to the left in Fig. 3) will close the valve a corresponding amount. The outer end of head 9a of the plunger is preferably provided with a tubular extension 9c, for the purpose hereinafter explained.

The outer end of cylinder 10 is interiorly threaded as at 10b for the reception of the threaded end of a tube 11, preferably of copper, which is connected directly to the pressure side of centrifugal pump E. Preferably cylinder 10

has a drain 10d in one side and has an annular recess 10e opposite drain 10d into which seepage of fluid may pass and be removed through drain 10d in order to prevent freezing in cold weather.

5 On valve body 1, at the side of disk 7 opposite to cylinder 10, is a lug 12 having a cylindrical bore 12a in axial alignment with plunger 9, said bore receiving the inner end of a sleeve 13 secured in bore 12a in any desired manner, the 10 sleeve 13 preferably having an annular shoulder 13a at one end for properly positioning the sleeve in the bore. The outer end 13b of the sleeve is preferably reduced in diameter and is externally threaded to receive the thimble 14 which is preferably closed at its outer end 14a except for an axial opening 14b for the passage of the sleeve 15 of a rod 17, hereinafter referred to. Sleeve 13 has a stepped bore 13c—13d therein, the smaller bore 13c being disposed at the end of 15 the sleeve adjacent disk 7, an annular abutment or shoulder 13e being formed at the junction of said bores.

Sleeve 15 of the rod 17 is preferably tubular and provided with internal threads 15a at its outer 20 end, and with a cylindrical head 15b at its inner end adapted to slidably fit within the larger bore 13d of sleeve 13, and a compression coil spring 16 is housed within bore 13b around sleeve 15, said spring being interposed between the head 25 15b of sleeve 15 and the end 14a of thimble 14 so as to normally yieldably maintain the head 15b abutting against the shoulder 13e. The compressive strength of spring 16 is controlled by adjustment of the thimble 14 on the threaded portion of sleeve 13.

30 Rod 17 has a threaded end 17a engaging the internally threaded portion 15a of sleeve 15 whereby rod 17 may be adjusted axially of the sleeve. Rod 17 extends beyond head 15b, through bore 13c of sleeve 13, and to a point somewhat in advance of sleeve 13, said rod telescoping the tubular extension 9c of the head of plunger 9. A compression coil spring 18 is housed within bore 13c around rod 17 and interposed between head 15b and the end of the tubular extension 9c which 35 is of smaller diameter than the bore 13c so that the extension 9c may enter said bore 13c; and spring 18 normally urges plunger 9 into the position shown in Fig. 3 in which the head 9a contacts directly with the adjacent end of cylinder 50 10, in which position butterfly valve 5 is in fully open position.

The normal function of spring 18 is to hold 55 plunger 9 in a retarded position and thereby keep butterfly valve 5 in an open position until some predetermined pressure working against plunger 9 forces this spring to compress, and while it is true that spring 18 would in common practice operate at lower pressure than would spring 16 60 yet it should not necessarily be referred to as a low compression spring as it holds butterfly valve 5 in an open position at all times when the pump is not in operation. This is an important feature in connection with fire apparatus where the full 65 horse-power of the motor is required for operating the fire truck.

The operation of the governor is as follows: The rod 17 is adjusted in sleeve 15 to limit the maximum horse-power of engine A to any desired 70 closure of the butterfly valve 5 to prevent horse-power overload on the pump transmission shaft F. As an example, if a governor is mounted on an engine which will develop 100 horse-power when the throttle is wide open, and it is known that the pump requires only 75 horse-

power, the rod 17 should be adjusted so that the butterfly valve is fixed to open just the required amount to permit the engine to drive the pump at the required capacity and pressure.

A partial closing of butterfly valve 5 does not necessarily, in actual practice, limit or restrict the normal working speeds of the engine, as the governor will limit horse-power without necessarily limiting or affecting speed of the engine. A partial closing of valve 5 has the effect of controlling the horse-power output of the engine at all speeds within its normal working speed range; therefore, with the horsepower of the motor lessened because of the adjustment of rod 17, a pump driven by this motor can still be operated to the higher speeds normally required to cover a practical range of service conditions. For instance, a pump rated for 500 G. P. M. (gallons per minute) underwriter's requirements must have a capacity of 500 G. P. M. at 120# pressure, 250 G. P. M. at 200# pressure, 167 G. P. M. at 250# pressure. 10 15 20

At the higher speed necessary to obtain the 250# pressure, for example, should the discharge head be reduced to 120#, the capacity would be very much increased over that obtainable from the pump when it was running at the required speed for the 120# pressure rating, and the horsepower required would also be very much greater. Therefore, a 500-gallon pump requiring 53, 58 and 63 B. H. P. respectively on the three 30 above-mentioned capacities and pressure requirements could at the speed necessary for the 250# test actually deliver say 700 gallons per minute requiring possibly 90 horse-power. It may be that the pump transmission in a given pump is 35 not suitable for over 80 H. P. and one of the functions of the speed governor would be to prevent more than 80 H. P. going through the pump. An engine capable of developing 100 H. P. at a certain speed with wide open throttle could operate 40 at the same speed delivering with say 20% closure of the butterfly valve in the governor. It is this function of horse-power limitation without necessarily restricting the speed that is very important. 45

The spring 18, which is a light buffer spring, permits plunger 9 to move towards rod 17, thereby initially partially closing the butterfly valve 5 an amount corresponding with the setting of rod 17 when a certain pressure, or more, is exerted on the plunger 9, said pressure being the pressure of fluid at the outlet of pump E transmitted to cylinder 10 through tube 11. Such pressure may be, say, approximately five pounds, under which the piston 3 will move towards rod 55 17 against the action of spring 18 until the tubular extension 9c has fully telescoped the end of rod 11, and the parts are in the position shown in Fig. 4. Such movement of the plunger will somewhat close the butterfly valve 5, depending upon 60 the setting of rod 17 in sleeve 15, and the plunger 9 will remain in this position as long as the requisite pressure of five pounds or more, is exerted by the pressure side of pump E upon the plunger in cylinder 10. 65

The first movement of the plunger 9 is effected by most any pressure that the pump might develop in operation, so that primarily, the closure of the butterfly valve to whatever extent it is determined by tension of spring 18 and the position of rod 17 with relation to the inner end of tubular section 9c is the limiting control of horse-power with no effect upon speed so long as a certain horse-power dependent upon the amount of fuel that will pass through the gover- 70 75

nor in that position is not exceeded. In other words, an engine may require a wide open throttle to deliver 100 H. P. at 4000 R. P. M. but might deliver 80 H. P. with a 20% closure of the governor throttle valve and still run at 4000 R. P. M.

Further movement of plunger 9 in direction to close valve 5 is yieldably prevented by the compression coil spring 16 acting against the head 15b of sleeve 15; but when the pressure on the plunger is sufficient to overcome the compression of spring 16, the plunger 9 acting through rod 17 will move sleeve 15 into the position shown in Fig. 5 against the action of spring 16, thereby further closing the butterfly valve 5 and reducing the amount of fuel passing to the engine cylinders. Spring 16 may be adjusted by setting thimble 14 so that the spring 16 will yield when the desired maximum fluid pressure at the outlet of pump E has been attained, and such movement of sleeve 15 will throttle the engine to reduce the speed thereof, and will control the maximum pressure that the pump may develop and thus avoid damage to pump or hose line as a result of excessive pressures. Spring 16 is preferably of such strength that it will compress over a range of piston pressures to meet the exact requirements for the individual unit, said spring pressure being rendered variable by adjustment of the threaded thimble 14 on the outer end of sleeve 13 to vary the tension of spring 16 which can be so set that when the predetermined maximum pressure is reached the butterfly valve 5 will be sufficiently closed to prevent setting up of higher pressures in the pump.

When the pump E is in disuse, or the pressure developed by the pump is less than the predetermined pressure in cylinder 10, the spring 18 will automatically return the butterfly valve 5 to its normally wide open position shown in Figs. 2 and 3, permitting the engine to develop to full power subject to the usual manually operated carburetor control (not shown) of the engine.

In Fig. 6 a modification is shown in which the governor is adapted for use in connection with a V-type engine having a double intake manifold, the valve body being provided with two bores 2a, the shaft 4 extending transversely through both bores and carrying butterfly valves 5a disposed in the respective bores; but the operation of the governor shown in this modification is the same as that described in connection with Figs. 1-3.

Use of my governor will therefore automatically limit the horse-power output of the prime mover to a predetermined maximum, and will also automatically limit the outlet pressures created by the centrifugal pump to a predetermined maximum, thereby preventing injury to the pump, hose line, or pump transmission shaft.

The valve body may be further modified to suit other types of engines and manifolds, and I do not consider my invention restricted to use only in connection with internal combustion engines for obviously same may be applied to turbines or other prime movers having valved fuel inlets.

Although this governor is particularly well adapted for application to a centrifugal pump with gasoline engine for fire service, it is not intended to limit the invention to a centrifugal pump nor to fire service nor to a gasoline engine.

I claim:—

1. A governor comprising a valve body; a throttle valve in said body, a cylinder on said body; a plunger in the cylinder operatively connected with said valve; a guide mounted on the body opposite the plunger; a slide in the guide; a rod adjustably mounted in the slide and adapted to engage the plunger and permit the valve to close a predetermined amount at predetermined pressures in the cylinder; yielding means reacting to normally maintain the valve in open position; and means associated with the slide and adapted to yieldably prevent further closing of the valve until a predetermined higher pressure is attained in the cylinder.

2. A governor comprising a valve body; a throttle valve in said body, a cylinder on said body; a plunger in the cylinder operatively connected with said valve; a sleeve on the body opposite the plunger; a slide in the sleeve; a rod on the slide adapted to engage the plunger and permit the valve to close a predetermined amount at predetermined pressures in the cylinder; a spring around the rod interposed between the slide and plunger for normally maintaining the valve in open position; a closure for the end of the sleeve; and means reacting to normally yieldably prevent further closing of the valve until a predetermined higher pressure is attained in the cylinder.

3. A governor comprising a valve body; a throttle valve in said body, a cylinder on said body; a plunger in the cylinder operatively connected with said valve; a sleeve on the body opposite the plunger; a slide in the sleeve; a rod adjustably mounted on the slide and adapted to engage the end of the plunger and permit the valve to close a predetermined amount at predetermined pressures in the cylinder; yielding means reacting to normally maintain the valve in open position; a thimble threaded on the end of the sleeve; and a spring in the sleeve interposed between the slide and thimble and adapted to yieldably prevent further closing of the valve until a predetermined higher pressure is attained in the cylinder.

BEN D. BARTON.
